CONTROL APPARATUS

Arthur S. Peterson, Marseille, Ill., assignor to
Certain-Teed Products Corporation, New York,
N. Y., a corporation of Maryland

Application August 3, 1940, Serial No. 350,247

5 Claims. (Cl. 259—23)

This invention relates to an apparatus for suspending a comminuted solid material in a liquid, especially to the process and apparatus for effecting such suspension in a continuous economical manner. The invention particularly relates to the mixing or incorporation of filler materials, usually of mineral character, in asphalt used for coating sheets of asphalt roofing.

In the production of composition roofing a web of felt, usually containing fibers derived from rags, paper, wood and other cellulosic materials, is saturated with asphalt and thereafter has applied thereto a coating of asphalt. In order to obtain the desired resistance to the weather, heat, moisture and other conditions to which such roofing is subjected and to secure a suitable thickness of the coating on the sheet, it is customary to incorporate in the coating material, that is, the coating asphalt, a powdered mineral material such as slate flour or ground limestone. These filler materials increase the resistance of the coating to plastic flow when the roofing is laid on the roof and exposed to the heat of the sun and also increase the resistance of the coating to weathering because of the opacity which is added to the coating by these materials. It is an important quality desired in a roofing sheet that means shall be provided to prevent to as great a degree as possible the actinic rays of the sun reaching the saturating asphalt carried by the felt, thus to preserve the saturant and the coating from the destructive effects of the rays of the sun and, as well, from the drying out of the protective oils in the saturant.

In many cases asphalt roofings are surfaced with a protective surfacing of comminuted material, such as granular slate, crushed brick, ceramic granules and other types of surfacing materials which also serve to a great extent to prevent the rays of the sun from reaching the underlying coating and the saturant therebeneath. In such surfaced roofing sheets it is necessary that the coating shall have proper qualities of adhesion or grip upon the granules applied thereto. This is accomplished in part by providing suitable wetting properties in the adhesive coating material, that is, the asphalt. These properties may be secured and modified by the incorporation of the filler materials above referred to.

In order to control the above-mentioned and other conditions of roofing manufacture it is particularly desirable that the filled coating shall be maintained with a uniformity of mixture, that is, with a uniform ratio of the comminuted

filler to the asphalt in which it is mixed. The amount of filler material carried by the filled coating may vary between 25 and 50% but in the usual case about 35 to 40% of the filled coating is represented by the filler material. In any case variations in the percent of the filler carried by the coating are undesirable because thereby the resistance and other physical qualities above referred to will vary with a resulting unsatisfactory product. Uniformity of mixture assists in insuring that the coated sheet has a coating of uniform quality throughout its extent.

Heretofore it has been the practice to deliver the dry comminuted filler materials and the asphalt coating material to the mixing apparatus manually or with manual control. The intermixing of the filler and the coating then has been carried out as a batch operation. Because of inadequate or inconvenient means of measurement of the quantities of the filler and asphalt delivered to the mixer this batch operation frequently resulted in non-uniformity of the mix. Moreover, variations in the quality of the mixed product occurred because of variation in the completeness of the mixture which was effected by such a batch operation.

It is an object of the invention to provide apparatus for utilizing it which will secure a continuous supply of intermixed liquid and comminuted material having a uniform quality of mixture.

It is a further object of the invention to provide for variation of the ratio of the comminuted material to the liquid material so as to secure different desired mixtures while maintaining substantially continuous operation.

It is a feature of my invention that I provide a positive continuous delivery or feed to the mixing chamber of each of the ingredients of the mix, that is, of the asphalt and of the filler material. Moreover, these materials each are fed in this continuous manner in controlled amounts so that the quantity or the volume thereof is measured and thereby the ratio of one to the other predetermined.

Cooperating with the two means for effecting delivery of the respective ingredients, namely, the asphalt and the comminuted material to the mixer, I provide means for varying the rate of delivery of one such delivery means relative to the other. This means for variation of the relative deliveries may take the form of a power transmission means connected between the two delivery means, which power transmission means is of such construction and arrangement that

the rate of operation of one delivery means may be varied relative to that of the other. A variable speed drive or transmission of conventional design may be used. By virtue of a power means connected to both said delivery means and to said transmission means delivery of the two ingredients may be effected concomitantly and the rate of one may be adjusted to the desired amount in relation to the rate of the other by varying the adjustment or setting of the transmission means.

The invention may utilize as part of this apparatus a metering pump or other fluid forcing means for delivery of the asphalt to the mixer from a suitable source containing the asphalt which has been raised in temperature to such an extent as to provide the necessary fluidity. The apparatus also may include a means, such as a conveyor or other means for transporting solid material, which is of a type which will determine by its rate of operation the amount of material so delivered to the mixer for incorporation in the asphalt.

It is a particular feature of the invention that means are provided for controlling the operation of the means for delivering or feeding the ingredients so that the amount of material being mixed in the mixing chamber shall be maintained within desired limits and that a sufficient amount of such material shall be acted upon by the mixing device operating within the chamber to secure substantially uniform mixing. The control means is constructed so as to be actuated upon variation in the amount of the material contained within the mixing chamber and acts to control the operation of the respective feeding or delivery means, preferably to initiate their operation substantially simultaneously and likewise to cut off their operation at the same time. In this manner the ratio of the amounts of the materials being delivered or of their volumes may be controlled and the mixing may be carried out continuously. The mixed material may, therefore, be continuously withdrawn from the mixing chamber with the assurance that a uniform mixture shall have been effected because of the requisite delivery in the proper proportions of the ingredient materials made possible under the control of the invention.

Further objects and advantages of my invention will be understood from the following description in connection with the drawing, in which

The single figure is a diagrammatic representation of the apparatus of the invention.

In the figure is shown a mixer 1 comprising a mixing chamber 3 containing the materials being mixed, and a mixing device, of which the top member or paddle 5 is shown, which may be supported and driven in any suitable manner. The chamber 3 is provided with an outlet conduit 6 for withdrawal of filled coating therefrom.

Conduit 7 is connected to a supply of asphalt heated to the proper fluidity for mixing. Metering pump 8 feeds the asphalt from conduit 7 to conduit 10, through which the asphalt is delivered to the mixing chamber 3. A suitable metering pump for fluid asphalt in this application is a gear pump which is steam jacketed or otherwise heated to maintain the proper temperature of the fluid asphalt.

A bin or hopper 11 containing filler material 12 is provided with a measuring screw feeder 13 driven by sprocket 15 on shaft 14. The discharge of the measuring screw 13 is delivered

through conduit 17 into the mixing chamber 3.

Power drive means, such as the motor 20 in the particular embodiment shown, is provided to drive the metering pump 8 and the metering feed screw 13 of the filler supply hopper. The motor 20 is provided with a dual sprocket 22 which by means of chain 23 drives the sprocket 16 on the shaft 9 of the asphalt metering pump 8 and by means of chain 25 drives sprocket 21 of a variable speed transmission unit 28. Sprocket 29 of the variable speed transmission unit 28 is connected by chain 24 to drive the sprocket 15 on the shaft 14 of filler feed screw 13. The ratio of speeds of the sprockets 21 and 29 may be changed and adjusted by adjustment of the hand wheel 26 on the transmission unit 28.

The control apparatus of the invention is generally indicated by the numeral 30 and comprises an inverted air bell 32 having the open end 33 thereof positioned within the chamber 3 adjacent or substantially at or below the level at which, for proper mixing, the fluid asphalt with which the filler is being mixed is to be maintained. A U tube manometer 34 having an open leg 36 and a closed leg 38 is connected to the bell 32 by a pressure transmitting conduit, such as a capillary tube 35, for transmitting the pressure of the air which becomes trapped in bell 32, as the level of the asphalt rises above the lower end of the bell, to the closed leg 38 of the manometer 34. The manometer 34 contains a suitable liquid 37 which may be water, oil or any other fluid which is in substantially stable liquid state at ordinary temperatures.

Positioned in the open leg 36 of the manometer 34 is a float 40 connected by stiff arched arm 42 to end portion 44 of lever 46. The lever 46 is pivoted at 48 intermediate the ends 44 and 50 thereof for free movement in the plane of the figure and has mounted for movement along end portion 50 thereof a weight 52. Also mounted upon the lever in a suitable position is a switch 54 which may operate by the tilting of the lever 46. The switch may comprise a glass tube having contacts sealed therein and containing a globe of mercury which when the tube is tilted in one position bridges across the contacts and completes the circuit and when the tube is tilted oppositely breaks the circuit. This type of mercury switch is commercially available under the trade-name "Mercoid."

The switch 54 is connected in series with the power supply lines 60 and the motor 20 through a suitable control, such as rheostat 62 adjusted by manual control knob 64, for varying the speed of the motor.

The operation of the device shown in the figure is as follows: The paddle 5 of the mixer is kept in constant movement while the roofing machine is being operated. When the quantity of material 4 in the mixer chamber becomes reduced, due to withdrawal of filled coating through the conduit 6, the pressure within the air bell 32 and also in capillary tube 35 and closed leg 38 of the manometer decreases, causing the liquid 37 contained in the open leg 36 of the manometer 34 to fall. Float 40 connected by arm 42 to end 44 of lever 46 likewise is lowered and causes the lever 46 to assume a tilt with the end 44 lower than the end 50. With a given adjustment of the parts the mercury switch 54 will be closed by the tilting of the lever 46 when the pressure in the bell 32 has fallen to a certain amount corresponding to a lowered level, such

as line X—X, of the materials in the mixer. The circuit through the rheostat 62 to the driving motor 20 from the power supply 60 will thereby be completed and the motor will be started.

The motor 20 through drive chains 23 and 25 drives the sprockets 16 and 27 of the metering pump 8 and transmission unit 28. By means of chain 24 sprocket 29 of the transmission unit 28 in turn drives sprocket 15 on shaft 14 of the filler feed screw 13. Positive drive of the metering pump 8 and the filler feed and measuring screw 13 thus is effected in a predetermined relation one to the other.

Both the metering pump 8 and feed screw 13 are positive displacement devices so that for a given rotational movement thereof a predetermined volume or amount of material is delivered to the mixer chamber 3. The ratio of the amount of filler material to the amount of asphalt may be varied at will by means of handwheel 26 on unit 28 which allows adjustment of the rotational speed of the filler measuring feed screw drive sprocket 29 with respect to the rotational speed of the metering pump sprocket 16. When, however, the handwheel 26 is properly adjusted to give the desired percentage of filler in the coating it is unnecessary to change the adjustment unless the conditions under which the asphalt and filler are being fed become changed or it is desired to modify the mix.

In order to provide for continuous operation and the continuous control of the mixing of the filler and the coating it is desirable to set the speed of the motor 20 so that the delivery of the filler and of the coating to the mixer chamber 3 will approximate the withdrawal of the filled coating therefrom. If the rate of withdrawal of the filled coating through the conduit 6 exceeds the total quantity of coater and filler received by the chamber 3 from the conduits 10 and 17, the speed of the motor 20 may be manually adjusted by means of knob 64 of rheostat 62 to speed-up the motor 20 and enable it to deliver the materials in amounts approximating the withdrawal. Conversely, with a reduced withdrawal of the filled coating the speed of the motor may be reduced until feed of the materials approximates the withdrawal.

The operation of the control device 30 then may act to maintain the requisite amount of material within the mixer for proper mixing and with the necessary amount of material overlying the paddle 5. When withdrawal of the filled coating from the mixer ceases or is reduced or for some other reason the level of the materials in the mixer rises, the pressure in the air bell becomes increased, thus raising the height of the liquid in the open leg 36 of the manometer 34 causing float 40 to lift the end 44 of the lever 46. The mercury switch 54 may thus become tilted to its "off" position thus stopping the motor 20 and feed of the fluid asphalt coating and of the filler to the mixing chamber 3. By suitable adjustment of the parts this action may be made to occur when the level of materials in the mixer has risen to a predetermined line Y—Y. If withdrawal of the filled coating from the mixer chamber 3 continues the level will thereafter fall for the time during which the motor and the feeding means remain stopped. By suitable adjustment of the parts, as the float 40 falls with the level in the open leg 36 of the manometer, with the fall of the level of the materials in the mixing chamber 3, the switch 54

again becomes tilted to the "on" position with the corresponding starting of the motor and of the coater and filler feeding devices. Thus within limited variation predetermined quantities of filler material and coating are maintained within the mixing chamber for mixing therein. Continuous operation of the mixing device within the chamber 3 upon a substantially constant amount of material thus is insured and uniform mixture thus may be obtained when the quality of the materials as they are delivered to the mixer, that is, the asphalt and the filler, and the temperatures and other conditions thereof remain constant.

It is to be understood that suitable heating means, not shown in the figure, may be incorporated in the asphalt feed lines 7 and 10 and in the metering pump 8 in order to keep the asphalt coating in the liquid state. Likewise means may be provided for heating the mixing chamber 3 and the discharge conduit 6 to prevent the asphalt from solidifying therein.

The remote actuated control device indicated generally at 30, avoids difficulties which, particularly with viscous and solid materials such as asphalt and filler, would be encountered with a conventional float type of level control, in which a float is directly in contact with the liquid to be regulated. If such a conventional float control were to be used in my apparatus the float would soon become weighted down with asphalt accumulated thereon and no longer operate accurately. By using an air bell 32 of sufficient diameter, that is, about 2½" to 4" diameter, I have found that accumulation of asphalt on the sides of the air bell has a negligible effect on the operation of the level actuated control device of my invention while retaining a sufficient limitation of the volume of air in the bell for sensitive actuation of the device.

The mounting of the weight 52 for movement along end portion 50 of lever 46 permits adjustment of the height of level desired to be maintained in the filler mixer chamber 3. When the weight 52 is positioned to the left of the position shown in the figure, a lower level will be maintained in the mixer chamber 3 and when to the right of the position shown in the figure a higher level will be maintained. Adjustment of the position of the weight 52 may also be required to compensate for heating of the air within the air bell 32 when the apparatus becomes heated by the hot materials being mixed. Such heating would cause an abnormal increase in pressure in the air bell out of proportion to the height of filled coating in the mixer chamber 3.

The particular embodiment illustrated is an example of one form of my invention. It is to be understood that modifications in construction and arrangement of the parts may be made without departing from the spirit of my invention. For example, in place of the manometer shown in the drawing I may substitute any suitable pressure responsive control device such as a diaphragm operated switch. Also, in some cases, I may substitute for the mercury switch 54 mounted on the lever 46 a contact point carried by the float 40 or an extension thereof to close the electric circuit. Other types of feeding devices for the coating and filler may be used and the amount of material fed may be determined by other means for example, by valves or separate metering devices rather than by the metering feed device itself.

Having thus described my invention, I now claim:

1. Apparatus for effecting suspension of a dry comminuted material in a liquid comprising a mixing chamber, means for positively feeding metered amounts of said liquid and of said comminuted material to said mixing chamber, continuously acting means within said chamber for effecting intermixture of said liquid and said comminuted material, means connected to said chamber for continuously effecting withdrawal of the intermixed material therefrom, and control means responsive to variations in the level of material contained in said mixing chamber, said control means being connected to said feeding means to actuate said feeding means substantially simultaneously to initiate said feed of said liquid and of said comminuted material to said mixing chamber when the amount of material being mixed in said chamber falls to a predetermined quantity and to stop said feed when said material within said chamber reaches a predetermined quantity, said control means being ineffective to initiate or stop action of said mixing means.

2. Apparatus for mixing asphalt and a comminuted filler material comprising a mixing chamber, continuously acting means within said chamber for effecting intermixture of fluid asphalt and comminuted filler material fed thereto, a metering pump connected to deliver asphalt from a supply to said chamber, screw feeding means for effecting feed of measured quantities of filler material from a supply to said chamber, power transmission means connected between said metering pump and said screw feeding means, said transmission means being constructed and arranged to be variable at will to change the relative speeds of said metering pump and said screw feeding means, power means connected concomitantly to drive said pump and said screw feeding means, an air bell positioned within said chamber with the open end thereof adjacent the level desired to be maintained in said mixing chamber, and control means operated by the rise and fall of pressure in said air bell upon rise and fall of the level of the materials in said chamber and connected to said power means to actuate said power means to initiate and to stop drive both of said metering pump and said screw feeding means, said control means being ineffective to initiate or stop action of said mixing means.

3. Apparatus for mixing a liquid and solid comminuted filler material which comprises a mixing chamber, continuously operating means within said chamber for effecting mixture of said liquid and said filler material, means for delivering liquid to said mixing chamber, means for delivering filler material to said mixing chamber, power means connected concomitantly to actuate both said delivery means, an air bell having the open end thereof positioned in said chamber adjacent the minimum level of the mixed liquid and filler material within said chamber, means responsive to variations in pressure within said air bell caused by variations in said level of mixed material in said chamber and acting upon said power means to stop and start the same in accordance with the rise and fall of said mixed material in said chamber to stop and initiate delivery of both said liquid and said filler material, said last means being ineffective to stop and start said mixing means, and means for continuously withdrawing from said chamber the liquid and filler materials mixed therein.

4. Apparatus for mixing a liquid and a solid comminuted filler material which comprises a mixing chamber, continuously operating means mounted within the chamber for effecting mixture of said liquid and said filler material, means for delivering the liquid to the mixing chamber, means for delivering the filler material to said mixing chamber, power driven means connected to both said delivery means concomitantly to actuate both said delivery means, means responsive to variations in the level of the materials being mixed in the mixing chamber for controlling said power driven means and thereby to control the delivery both of said liquid and of said filler material to said chamber to maintain therein a predetermined quantity of said materials being mixed, said control means being connected to said power driven means to actuate said power driven means independently of said continuously operating mixing means.

5. Apparatus according to claim 4 which comprises means operable at will connected to both said delivery means for varying the ratio of the amounts of said liquid and of said comminuted filler material delivered to said chamber.

ARTHUR S. PETERSON.
